UNITED STATES PATENT OFFICE.

ALLEN LOOMIS, OF DETROIT, MICHIGAN, ASSIGNOR TO PACKARD MOTOR CAR COMPANY, OF DETROIT, MICHIGAN, A CORPORATION OF MICHIGAN.

CARBURETER.

1,399,065.

Specification of Letters Patent.

Patented Dec. 6, 1921.

Application filed November 13, 1915. Serial No. 61,282.

To all whom it may concern:

Be it known that I, ALLEN LOOMIS, a citizen of the United States, and resident of Detroit, Wayne county, State of Michigan, have invented certain new and useful Improvements in Carbureters, of which the following is a specification.

This invention relates to carbureters for hydrocarbon motors.

One of the objects of the invention is to provide a carbureter in which the gases pass downwardly therethrough.

Another object of the invention is to provide a carbureter with a Venturi tube and a gasoline nozzle having side openings.

Another object is to provide a drain for a carbureter which has its mixture outlet at the lower part of the mixing chamber.

A further object is to provide an automatically closed drain for a carbureter.

Other objects of the invention will appear from the following description taken in connection with the drawings which form a part of this specification and in which:

Figure 1 is a front elevation of a motor and carbureter embodying this invention;

Fig. 2 is an enlarged transverse section of the carbureter shown in Fig. 1;

Fig. 3 is a section on the lines 3—3 of Fig. 2; and

Fig. 4 is a sectional view of another form of carbureter.

Referring to the drawings, it will be seen that a carbureter is shown as applied to a motor of the V-type, but it will be understood that some of the features of this invention may be used with other types of motors.

Referring particularly to Fig. 1, 10 indicates one of the side members of a frame of a motor vehicle upon which a V-type motor 11 is mounted. This V-type motor is provided with two sets of cylinders 12, 13, and a carbureter 14 is mounted between the cylinders and connected therewith through passages or conduits 15 and an inlet manifold 16, said manifold being shown as formed integrally with the cylinder castings.

Said latter conduit 16 leads through a port 16' into the interior of the cylinder, and said port is shown as closed by the usual puppet valve 16''. In Fig. 1, the right hand cylinder casting is broken away to illustrate these conduits, and it will be understood that there

are similar passages or conduits in the cylinder block at the left hand side.

The carbureter illustrated in Figs. 1 to 3 comprises principally a body portion or mixing chamber 14, a float chamber 17 of usual construction, a mixture or Venturi tube 24 arranged within the body portion, an air inlet piece 18, the interior of which communicates with the upper end of the Venturi tube, a supplementary or auxiliary air inlet piece 19 which forms an extension on one side of the body portion of the carbureter and which communicates with the mixing chamber, a fuel or gasoline nozzle 21 which extends upwardly into the mixture tube, and one or more mixture outlets or passages 15, which latter have been heretofore referred to.

It will be understood that the upper end of the Venturi tube 24 is always open to the atmosphere through the openings 18' in the inlet piece 18. Also, the interior of the body of the carbureter communicates through the outlets 15 and conduits 16 with the motor cylinders. The auxiliary air inlet 19 is controlled by the usual puppet valve 19' and springs 19''.

From the above description, it will be seen that the suction created in the motor cylinders will cause air to be drawn through the inlets 18 and 19, the Venturi tube 24, the body of the carbureter, and the conduits 15 and 16 into the motor cylinders. As the air drawn through the inlet 18 passes openings 23 in the upper part of the nozzle 21, fuel or gasoline is picked up and carbureted to form the combustible mixture. The openings 23 are arranged in the side of the nozzle so that the downward pressure of the air passing through the Venturi tube will not affect the feed of gasoline through the nozzle. As shown, these openings 23 are four in number, arranged around the nozzle in substantially the same horizontal plane, and approximately at the most constricted portion of the Venturi tube. Thus, the openings are arranged at the point where the air is passing at its greatest speed.

The nozzle 21 is suitably mounted in the body of the carbureter, and its interior is connected through a cross passage 25 and a conduit 20 with the float chamber 17, as shown particularly in Fig. 3.

In the branched arrangement of the carbureter shown in Figs. 1 to 3, two throttle

valves 27 are provided. The usual butterfly throttles are shown, and they are connected for simultaneous operation by arms 31 on the pins 28, upon which the throttles are 5 mounted, links 32, and arms 30 on a rod 29. The oscillation of the rod 29 thereby simultaneously controls the positions of both throttle valves.

For the purpose of carrying off excess 10 gasoline that may condense or otherwise collect in the mixing chamber of the carbureter, a drain is provided from each of the outlets or passages 15. These drains, indicated at 33, connect at 34 and pass 15 through a valve chamber 35 to a pipe 36 which extends to adjacent the bottom of the motor as shown in Fig. 1. Since the drains connect with the carbureter on the suction side of the Venturi tube they would seriously 20 interfere with the mixture if left open when the motor is running. To automatically close these drains a valve 37 is arranged in the chamber 35 and a spring 38 supports the valve slightly off its seat so 25 that the ports 39 are open when the valve is at rest as shown in Fig. 2. In that position, which is the position of the valve when the motor is not running, the condensed gasoline may drain from the walls of the mixing 30 chamber through the drains 33, ports 39, and pipe 36 to the ground. When the motor is running, however, there is always suction or a partial vacuum in the passages 15 with which the drains connect and the valve 37 35 is therefore drawn up against its seat and closes the ports 39 so that no air can be drawn in through the drains to affect the mixture in the carbureter.

Fig. 4 shows another form of carbureter 40 in which the size of the opening in the gasoline nozzle may be adjusted and in which a single throttle valve is employed. The fuel is fed from the float chamber 17 by means of a tube 40 which turns at right angles and 45 forms a nozzle 41. This nozzle terminates within the Venturi tube 24 and has its end closed by an adjustable screw 44 threaded into a projection 42 in the nozzle.

The size of the side opening left between the head of the screw and the nozzle may be 50 adjusted by varying the position of the screw.

Below the Venturi tube and the nozzle is mounted a single throttle valve 46 for regulating the amount of mixture to be supplied to the engine. This valve is of the usual form and may be operated by an arm 48.

Specific embodiments have been shown and described but it is to be understood that 60 the invention is not limited thereto and that other embodiments may be made without departing from the spirit or scope of the invention.

Having thus described my invention, 65 what I claim and desire to secure by Letters Patent is:—

1. In a carbureter the combination of an air inlet, two mixture outlets below said inlet, a Venturi tube extending downwardly 70 from said inlet, a cross member between said outlets and a gasoline nozzle mounted on and extending upwardly from said cross member into said Venturi tube.

2. In a carbureter, the combination of an 75 air inlet, two mixture outlets below said inlet, a Venturi tube extending downwardly from said inlet, a cross member between said outlets, a gasoline nozzle mounted on and extending upwardly from said cross member 80 into said Venturi tube, and a drain for condensed gasoline between said outlets and below said cross member.

3. In a carbureter, the combination of an air inlet, two mixture outlets below said 85 inlet, a Venturi tube extending downwardly from said inlet, a cross member between said outlets, a gasoline nozzle mounted on and extending upwardly from said cross member into said Venturi tube, a drain for condensed gasoline between said outlets and below said cross member and throttle valves 90 for each outlet at either side of said cross member.

In testimony whereof I affix my signature. 95
ALLEN LOOMIS.
